US0D1065578S

(12) **United States Design Patent** (10) **Patent No.:** **US D1,065,578 S**
(45) **Date of Patent:** **** Mar. 4, 2025**

(54) **LABORATORY INSTRUMENT**

(71) Applicant: **LIFE TECHNOLOGIES CORPORATION**, Carlsbad, CA (US)

(72) Inventors: **Timothy Barta**, Round Rock, TX (US); **John Staton**, Waltham, MA (US); **Robert Setterquist**, Boulder, CO (US); **Sandro Klein**, Irvine, CA (US); **Carolyn Johnson**, Boulder, CO (US); **Justin Inslee**, Broomfield, CO (US); **Jason Jones**, Erie, CO (US); **Christopher Crowley**, Golden, CO (US); **Ethan Gentert**, Longmont, CO (US); **Wade Lukianow**, Boulder, CO (US); **Sara Thiele**, Lafayette, CO (US); **Jay Greco**, Arvada, CO (US); **Syrus Jaffe**, Carlsbad, CA (US); **Eric Liu**, Austin, TX (US); **Alexandre Vlassov**, Simi Valley, CA (US); **Marie Gonzalez**, Austin, TX (US); **Christopher Martin**, Snohomish, WA (US); **Robert Smith**, Louisville, CO (US)

(73) Assignee: **LIFE TECHNOLOGIES CORPORATION**, Carlsbad, CA (US)

(**) Term: **15 Years**

(21) Appl. No.: **29/971,456**

(22) Filed: **Nov. 4, 2024**

Related U.S. Application Data

(63) Continuation of application No. 29/896,343, filed on Jul. 1, 2023, now Pat. No. Des. 1,054,583.

(57) **CLAIM**

The ornamental design for a laboratory instrument as shown and described.

DESCRIPTION

FIG. 1 is a top front isometric view of a laboratory instrument showing the claimed design;

FIG. 2 is a bottom rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures show portions of the laboratory instrument that form no part of the claimed design.

1 Claim, 8 Drawing Sheets
